(54) **ORNAMENTS, FROM ANTHRACITE COAL,
& C**

(76) Inventor: **Josiah W. Kirk**

Asaiah W. Kirk
Letters Patent.

The Schedule referred to in these Letters Patent and making part of the same containing a description in the words of the inventor of the said Asaiah W. Kirk himself of his improvement in making polished articles of ornament and use from anthracite or bituminous coal.

This discovery consists in making polished candlesticks, salt cellars, ink-stands, sand boxes, picture frames, clock cases, and mantles, ornaments, such as vases, garnitures &c out of anthracite or bituminous stone coal instead of other materials. The material may be reduced to the proper size shape and polish among other means, by having sawing, or grinding it down when a plain surface is wanted, or by a turning lathe and tools when a round surface is required, and then smoothed and polished by the use of fine stones, emery, charcoal or other materials of fine grit. The meritorious discovery of which I claim to be the discoverer and to have the right to a Patent in the use and application of anthracite or bituminous coal to the purpose of making the aforesaid polished articles of ornament and use, whether reduced to the proper size shape and polish by the above described or other means.

Witness my hand this fifth day of May 1801.

Asaiah W. Kirk
